UNITED STATES PATENT OFFICE.

ALBERT H. KUNDEE, OF DOWAGIAC, MICHIGAN, ASSIGNOR TO PREMIER WARM AIR HEATER COMPANY, OF DOWAGIAC, MICHIGAN, A CORPORATION OF MICHIGAN.

AUTOMATIC HUMIDIFIER FOR WARM-AIR FURNACES.

Application filed January 24, 1927. Serial No. 163,254.

This invention relates generally to automatic humidifiers for warm air furnaces and consists of certain novel features of construction, combinations and arrangement of 5 parts as will be more fully described and particularly pointed out in the appended claims.

In the drawings:

Figure 1 is a top plan view of the humidifier with the top of the casing removed;

Figure 2 is a detail view of the valve.

Figure 3 is a section taken on line 3—3 of Figure 2.

In the accompanying drawings wherein 15 like characters of reference designate like parts, the numeral 1 indicates a humidifier casing made in accordance with the present invention, 2 the valve therefor and 3 the float for operating the valve. In practice 20 it has been found that it is very desirable to have the casing 1 of as small an area as is practically possible. Therefore, as illustrated, one end of the casing designated at 4 is made only large enough to accommodate the float 3 and the side walls 5 of 25 the casing taper sharply inwardly so as to practically converge at the other end. However, sufficient space is allowed so as to provide for the end wall 6 which is 30 adapted to support the valve 2.

Because of the limited space within the casing at the point where the valve is supported upon the wall 6, a great deal of trouble has been encountered when it is desired to remove the valve for cleaning. It is 35 therefore one of the objects of the present invention to eliminate this objectionable feature by providing means for quickly and easily removing and inserting the valve in 40 the casing.

As shown the valve comprises a coupling 45 7 extending through the end wall 6 and which is provided with a headed portion 8 adapted to seat against the wall 6 within the casing 1. The coupling 7 is bored to form an inlet passage 9 which is reduced at its inner end and terminates in a tapered valve seat 10.

For connecting the float 3 to the valve, 50 a float rod 11 is provided having a plate 12 secured to one end thereof which in turn supports a needle valve 13 for cooperating with the valve seat 10 in controlling the flow

of liquid into the casing. As shown one end of the needle valve is slotted at 14 for enclosing an end of the plate 12 and is provided with a transverse opening 15 registering with an opening 16 in the plate. These 55 openings are adapted to receive a cotter pin 17 for pivotally mounting the needle valve 60 to the plate.

For pivotally connecting the float 3 within the casing the headed portion 8 of the coupling 7 is provided with a post 18 which 65 is bifurcated as at 19 similar to the needle valve and is positioned directly beneath the same. This post is also provided with a transverse opening 20 registering with an opening 21 in the plate 12.

Heretofore it has been the practice to 70 provide a cotter pin similar to the pin 17 for pivotally connecting the plate 12 to the post 18. However, as stated aforesaid because of the limited area within the casing 1 great difficulty has been encountered in 75 removing and inserting the pin, as practically no room is provided for the manipulation of a pin removing tool.

I have therefore obviated the necessity of 80 using a tool by providing a removable spring pivot pin 22. As shown this pin 85 consists of a substantially longitudinal spring rod portion 23 and a transverse pin portion 24 extending from one end thereof. The pin 24 is adapted to be inserted through 90 the openings 20 and 21 in the post and plate with the rod 23 extending rearwardly and having its outer end abutting against one of the side walls 5. Preferably the rod 23 is bowed outwardly to provide sufficient tension for holding the pin in place, and to further provide against any undue removal thereof the rod is provided with a slightly bowed end portion bent at an angle with 95 respect to the rest of the rod and forming a wall engaging portion 25.

As will be readily apparent the spring pivot pin 22 may be easily and quickly removed without the use of a tool by simply grasping the rod 23 and moving it toward 100 the wall 5. Likewise all that is necessary to install the valve is to align the openings 20 and 21 of the plate and post, insert the pin 24 and allow the rod 23 to spring back 105 against the wall 5. This provides a very simple arrangement for quickly and easily

removing and inserting the valve and is quite an improvement over the constructions now in use.

It will be noted that the extreme lower portion of the plate 12 is extended to form a projection 25' which is adapted to abut against the post 18 for limiting the downward movement of the float and float rod. The arrangement is such that even in the lowest position of the float rod the point of the valve is not withdrawn from the surface of the valve seat. It will therefore be apparent that while an adequate upward and downward movement of the valve is allowed for the efficient operation thereof, the valve is always guided in its opening and closing movement because of this arrangement.

It is very important in assembling the valve and the casing that it be placed in as near a true vertical position as possible. Therefore to facilitate the correct positioning of the valve, the end wall 6 is provided with vertical shoulders 26 which are positioned in such a manner that the distance between them is slightly less than the diameter of the headed portion or nut 8. This nut is of a standard construction which may be depended upon to be of substantially a certain diameter. Therefore before the coupling 7 can be placed in position and the nut be positioned between the shoulders 26, the sides of the nut must first be ground or filed to the size of the space between the shoulders. This will always insure a tight fit and prevent any looseness of the nut in the casing and thereby provide for the correct vertical position of the valve.

While it is believed that from the foregoing description, the nature and advantage of my invention will be readily understood, I desire to have it understood, that I do not limit myself to the specific construction shown and described and that such changes may be resorted to when desired as fall within the scope of the claims.

What I claim as my invention is:

1. In a humidifier for warm air furnaces, the combination of a casing having an enlarged end portion, side walls converging inwardly from said end portion to a point in close proximity to each other, an end wall connecting said converging side walls, a headed coupling supported by said end wall and having a passageway therethrough terminating in a valve seat within the casing, a post projecting from said headed coupling within the casing and provided with a transverse opening therethrough, a float rod within the casing having a float positioned at one end thereof in the enlarged end portion of the casing, a plate secured to the other end of said float rod and having an opening adapted to register with the opening in the said post, a valve carried by said plate and means for pivotally mounting said

float and valve within the casing comprising a removable pivot pin having one portion extending through the openings in the said post and plate and having another portion extending from said first mentioned portion and abutting against one of the converging side walls of the casing for holding the pin in position under tension.

2. In a humidifier for warm air furnaces, the combination of a casing having an enlarged end portion, side walls converging inwardly from said end portion to a point in close proximity to each other, an end wall connecting said converging side walls, a headed coupling supported by said end wall and having a passageway therethrough terminating in a valve seat within the casing, a post projecting from said headed coupling within the casing and provided with a transverse opening therethrough, a float rod within the casing having a float positioned at one end thereof in the enlarged end portion of the casing, a plate carrying a valve secured to the other end of said float rod and having an opening adapted to register with the opening in the said post, and a removable valve securing member having a pin portion extending through the openings in the said post and plate and a spring rod extending from said pin and having its free end abutting against a wall of the casing for holding the pin in position.

3. In a humidifier for warm air furnaces, the combination of a casing having an enlarged end portion, side walls converging inwardly from said end portion to a point in close proximity to each other, an end wall connecting said converging side walls, a headed coupling supported by said end wall and having a passageway therethrough terminating in a valve seat within the casing, a post projecting from said headed coupling within the casing and provided with a transverse opening therethrough, a float rod within the casing having a float positioned at one end thereof in the enlarged end portion of the casing, a plate carrying a valve secured to the other end of said float rod and having an opening adapted to register with the opening in the said post and a removable valve securing member including a spring rod extending longitudinally of the casing and having one end thereof abutting against a side wall of the casing and a transverse pin portion extending through the openings in the post and plate and secured to the other end of the spring rod.

4. In a humidifier for warm air furnaces, the combination of a casing having an enlarged end portion, side walls converging inwardly from said end portion to a point in close proximity to each other, an end wall connecting said converging side walls, a headed coupling supported by said end wall and having a passageway therethrough

- terminating in a valve seat within the casing a post projecting from said headed coupling within the casing and provided with a transverse opening therethrough, a float rod 5 within the casing having a float positioned at one end thereof in the enlarged end portion of the casing, a plate carrying a valve secured to the other end of said float rod and having an opening adapted to register 10 with the opening in the said post and a removable valve securing member comprising a relatively short pin portion extending through the openings in the post and plate transversely of the casing and a spring rod 15 portion extending longitudinally of the casing adjacent one side wall thereof and having one end abutting against said wall and having the other end secured to the transverse pivot pin.
- 20 5. In a humidifier for warm air furnaces, the combination of a casing having a portion of limited area, a support positioned within said portion of limited area having an opening therethrough, a plate carrying a 25 valve and having a portion thereof provided with an opening adapted to register with said support opening, said support having an inlet passage controlled by said valve and a removable valve securing member
- provided with a pin portion extending 30 through the openings in the said support and plate and a spring rod portion extending from said pin and having its free end abutting against a wall of the casing for holding the pin in position. 35
6. In a humidifier for warm air furnaces, the combination of a casing having a portion of limited area, a support positioned within said portion of limited area having an opening therethrough, a plate carrying 40 a valve and having a portion thereof provided with an opening adapted to register with said support opening, said support having an inlet passage controlled by said valve, and a removable valve securing member 45 provided with a pin portion extending through the openings in the said support and plate and an outwardly bowed portion secured to said pin and extending longitudinally of the casing, the free end portion 50 thereof being bent at an angle to the rest of the bowed portion and forming a wall engaging portion for holding the pin in position under tension. 55

In testimony whereof I affix my signature.

ALBERT H. KUNDEE.
